UNITED STATES PATENT OFFICE.

HERBERT L. HAIGHT, OF LANSING, MICHIGAN.

VENDING-MACHINE.

1,115,527.

Specification of Letters Patent.

Patented Nov. 3, 1914.

Application filed April 14, 1913. Serial No. 780,882.

To all whom it may concern:

Be it known that I, HERBERT L. HAIGHT, a citizen of the United States, residing at Lansing, in the county of Ingham and State 5 of Michigan, have invented certain new and useful Improvements in Vending-Machines, of which the following is a specification.

My invention relates to vending machines and has particular reference to machines of 10 this character for dispensing liquids, such as gasoline or the like.

An important object of this invention is to provide means of the above mentioned character, which are easy to operate, reliable in 15 such operation and comparatively simple in construction.

A further object of my invention is to provide means of the above mentioned character which will accurately dispense the proper 20 amount of the liquid, upon the insertion of a proper coin and the manual operation of elements thereof.

A further object of this invention is to provide means of the above mentioned character, which are primarily operated by a single crank or the like, the remaining elements 25 thereof being actuated by the movement of the crank and operating automatically.

A further object of my invention is to 30 provide means to positively lock the pump operating elements of the apparatus against rotation before the proper coin is inserted, such elements being automatically released upon the insertion of the coin and a slight 35 movement of the crank and associated elements.

A further object of the invention is to provide means to return the coin to the operator in the event that the apparatus does 40 not contain a sufficient amount of gasoline or the like.

Other objects and advantages of this invention will be apparent during the course of the following description.

In the accompanying drawings, forming 45 a part of this specification and in which like numerals are employed to designate like parts throughout the same, Figure 1 is a side view of the apparatus, parts thereof being shown in section, on line 1—1 of Fig. 2, and parts thereof broken away, Fig. 2 is an end view of the same parts being in section and parts removed, Fig. 3 is a horizontal section taken on line 3—3 of Fig. 1, Fig. 4 50 is a side view of the pumping means, parts

thereof being shown in section, and, Fig. 5 is a sectional view through the liquid fuel holding tank or receptacle, the elements disposed therein being shown in section.

In the drawings, wherein is illustrated a 60 preferred embodiment of my invention, the numeral 6 designates a casing or shell, of any well known or preferred type, within which are arranged the different operating elements of the apparatus, so that the same 65 cannot be tampered with.

Rigidly mounted within the shell 6, near and spaced from the upper end thereof, is a horizontal support or base 7, as shown. Rigidly mounted upon this base 7 are spaced 70 upstanding bearings 8, within which is rotatably mounted an operating shaft 9. This operating shaft extends outwardly beyond the shell 6 and is provided at its free end with a handle or crank 10, rigidly connected 75 therewith. The operating shaft 9 carries a ratchet wheel 11, rigidly mounted thereon. This ratchet wheel is provided with a laterally extending hub or sleeve 12, rigidly connected therewith and preferably cast integral with the same. The hub 12 is provided at its end with teeth 13, to engage with teeth 14 formed upon the end of a hub 15, forming a part of a small gear 16, which is rotatably mounted upon the operating shaft 9. The teeth 13 and 14 are preferably so arranged that the hub 12 may be rotated for substantially one-fourth of a revolution before the teeth 13 will engage the teeth 14 to effect the rotation of the hub 15 in the same direction. It is thus seen that the teeth 13 and 14 form a lost motion connection or clutch between the hubs 12 and 15. The hub 12 carries an upstanding post 17 and the hub 15 an upstanding post 18, which are connected by a suitably stiff retractile coil spring 19, the function of which is to return the hub 12 to its normal position when released. When the teeth 13 and 14 will be properly spaced, for allowing 80 the hub 12 to be turned for substantially one-fourth of a revolution before turning the hub 15, as above stated.

Rigidly mounted upon the base 7 are upstanding spaced bearings 20, through which 105 is journaled a rotatable shaft 21. This shaft 21 has a large gear wheel 22 rigidly mounted thereon, which permanently engages the small gear wheel 16, as shown. Rigidly connected with one end of the rotatable shaft 21 110

is a crank-disk 23, which operates within an opening 24 formed in the base 7, as shown.

Means are provided to normally lock the 5 large gear wheel or pinion 22 against rotation, comprising a movable or reciprocatory bolt 25, provided at its forward end with a tooth 26 to engage between the teeth of the gear wheel or pinion 22. The reciprocatory bolt 25 operates within a stationary guide bracket 27, rigidly mounted upon the base 7, as shown. Suitably connected with the reciprocatory bolt 25 is a curved rod or arm 28, connected at its opposite end with a head 29, carried by a reciprocatory rod or bolt 30. The rod or bolt 30 operates through a horizontal guide bracket 31, which is rigidly mounted upon a support 32, fixed upon the base 7. The reciprocatory rod or bolt 30 10 and the arm or rod 28 are adapted to be moved longitudinally simultaneously in the same direction, the same being in effect a continuous rod. Connected with the forward or free end of the rod or bolt 30 is a 15 retractile coil spring 33, which is attached to the shell 6 or other fixed support. The spring 33 normally holds the rod or bolt 30 in a forward position with the head 29 engaging the guide bracket 31, as shown in 20 Fig. 1.

The head 29 is provided upon its lower side with a longitudinal slot 34, for receiving the teeth of the ratchet wheel 11. This head is also provided with a vertical coin 35 slot 35, which leads into the slot 34. It is thus seen that when a suitable coin is inserted within the slot 35, the same will engage with the teeth of the ratchet wheel 11, which upon being turned in the direction of the 25 arrow will move the head 29 and associated elements longitudinally in the same direction, whereby the tooth 26 of the bolt 25 will disengage the teeth of the large gear wheel 22.

30 The rod or bolt 30 is provided upon its upper surface with a recess or notch 36, to be moved adjacent to and receive the end of a dog or pawl 37, upon the longitudinal movement of the same in one direction. The 35 free end of this dog or pawl operates through an opening 38 formed in the guide bracket 31, the same normally slidably engaging the rod or bolt 30. This dog or pawl 37 is pivoted, as shown at 39 upon 40 fixed ears or brackets 40.

Suitably mounted within the upper end of the shell 6 is a dispensing tank or receptacle 41 having connection at its lower end with a depending supply pipe 42, as shown.

45 The numeral 43 designates a tubular post mounted within the dispensing tank 41, as shown. Extending longitudinally through the tubular post 43 is a connecting rod 44, the lower end of which is forked and straddles the dog or pawl 37 and is pivotally con-

nected therewith, as shown at 45. Connected with the upper end of the tubular post 43 is a horizontal support or bar 46, upon which is rigidly mounted an upstanding ear or bracket 47. Pivotally connected with the 50 upper end of this bracket 47, as shown at 48, is a vertically swinging lever 49, having pivotal connection with the upper fork end of the connecting rod 44, as shown at 50. Rigidly connected with one end of the vertically swinging lever 49 and preferably formed integral therewith is an approximately U-shaped bracket 51, supporting a screw-threaded rod 52, rigidly attached thereto. 55

The numeral 53 designates a float-ball, which is longitudinally movably mounted upon the vertical rod 52 and held upon the same in adjustment at a desired position by nuts 54, disposed above and below the same, as shown. Adjustably mounted upon the opposite end of the lever 49 is a counter-weight 55, which is clamped in adjustment at a desired position upon said lever by means of a clamping screw 56 or the like. 60 It is thus seen that when the bolt or rod 30 is longitudinally moved to the right so that the free end of the dog or pawl 37 will enter the notch 36, upon the supply of the proper amount of liquid to the dispensing 65 tank 41 (by means to be hereinafter described), the float-ball 53 will be elevated, whereby the lever 49 will have its right end swung upwardly, to move the rod 44 upwardly. Upon this upward movement of 70 the rod 44 the dog or pawl 37 is elevated to release the bolt or rod 30, the spring 33 at once returning the same to its normal 75 position.

Connected with the lower portion or end 80 of the dispensing tank 41 is an outlet or discharge pipe 57, which extends outwardly beyond the shell 6 and is preferably connected with the hose 58 or other suitable conduit. Connected in the outlet pipe 57 85 is a valve structure 59 of any well known or preferred type, the valve of which (not shown), is operated by a stem 60, passing through a fixed guide bracket 61. Rigidly connected with the outer end of the stem 60 is a depending crank 62, having pivotal connection with a link 63, which is in turn 90 pivotally connected with an upstanding finger 64. This finger is provided at its lower end with an open head, for receiving the free end of the rod or bolt 30, the same 95 being clamped thereon by a screw 65. When the rod or bolt 30 is in its normal position, as shown in Fig. 1, the valve structure 59 is open to allow of the escape of the liquid 100 from the tank 41 but when the rod 30 is moved longitudinally to the right so that the end of the dog or pawl 37 enters the opening or notch 36, the valve structure 59 will be closed, the same having been oper- 105

ated by the finger 64, link 63 and depending crank 62, as is obvious. It is to be understood that any suitable form of valve may be connected in the pipe 57.

5 Disposed below the base 7 is pumping means, comprising a stationary upstanding cylinder 66, within which is mounted a piston 67. Pivotaly connected with this piston is a depending pitman 68, having pivotal connection with the crank-disk 23, as shown at 69. The lower end of the cylinder 66 is connected with a T-coupling 70, which is connected with a depending pipe 71 and the pipe 42. The pipe 42 has a check valve 72 connected therewith, as shown. The pipe 71 extends downwardly and leads into a liquid fuel holding tank or receptacle 73, as clearly shown in Fig. 5. The pipe 71 has a check valve 74 connected therewith.

10 20 Disposed within the tank 73 is a vertical pipe 75, within which is mounted a float 76. Connected with this float is an upstanding rod 77, pivotally connected at its upper end with a horizontal lever 78, which is pivotally mounted, as shown at 79, upon a fixed support 80.

The numeral 81 designates a coin chute, which is connected at its outer end with the shell 6 and at its lower end with the guide bracket 31, as shown. This coin chute conducts the coin to the slot 35. The coin chute 81 comprises an upwardly swinging section 82, pivoted, as shown at 83. The section 82 is pivotally connected with a rod 84, which extends downwardly and is pivotally connected with one end of the lever 78. Disposed below the coin chute section 82 is a housing 85, to deliver the return coin into a catching receptacle 86, through an opening 87. It is thus seen that when the liquid fuel held within the tank 73 falls below a certain level, the float 76 will descend, which through the connecting means will elevate the chute section 82, providing an opening 85 whereby the coin will fall into the housing 85 and return to the operator. Disposed forwardly of and near the ratchet wheel 11 is a coin catching receptacle 86', into which the coin falls upon the proper rotation of the ratchet wheel and after the coin has fulfilled its function.

The operation of the machine is as follows:—A coin 70^a is inserted into the outer end of the chute 81, and is conducted thereto by into the slot 35 of the head 29, to engage the teeth of the ratchet wheel 11, forming detachable connecting means between the head and the ratchet wheel. The operator now turns the handle 10 clock-wise for rotating the ratchet wheel 11 in the direction of the arrow, as shown in Fig. 1. When the handle 10 is first turned, that is before the same has been turned for substantially a quarter of a revolution, the shaft 9 being

15 25 30 35 40 45 50 55 60 65 70 75 80 85 90 95 100 105 110 115 120 125 130

and extension 12 will primarily turn the same but will not turn the small gear wheel 16 and extension or hub 15, until the teeth 13 engage the teeth 14, which takes place when the shaft 9 has been turned for a quarter of a revolution. Upon the partial rotation of the ratchet wheel 11 while the gear wheel 16 is stationary, as above stated, the head 29 and arm 28 are moved longitudinally to the right to withdraw the tooth 26 from between the teeth of the large gear wheel 22, such arm 28 being held in this position by the free end of the pawl or dog entering the opening or notch 36 of the rod or bolt 30, carried by the head 29. When the rod or bolt 30 is moved to the right so that the end of the pawl 37 enters the recess 36, the coin within the slot of the head 29 occupies a position at or near one side of the ratchet wheel, whereby the tooth which engages the coin will now tend to move the same downwardly for discharging it from the slot, the same being connected within the receptacle 86'. Attention is called to the fact that as the pawl 37 is now holding the rod or bolt 30 against returning movement, the tension of the spring 33 will be practically removed from the coin. In practice it has been found that no difficulty is experienced in operating the machine due to the failure of the coin to drop or disengage the ratchet wheel, but if the same should stick, it is obvious that the same may be readily released, after the pawl 37 has entered the recess 36, by turning the crank shaft 9 slightly in a reverse direction, it being remembered that the coin is now located near or upon one side of the ratchet wheel, the same falling within the receptacle 86'. The valve structure 59 is closed upon the movement of the rod or bolt 30 to the right. It is thus seen that the large pinion 22 is released and the locking means therefor will be held out of engagement therewith, until a proper amount of the gasoline or the like has been pumped into the dispensing tank 41. The crank 10 is now rotated freely in the same direction, the teeth 13 engaging the teeth 14, whereby the small gear 16 is locked to the shaft 9 for rotation therewith. The small gear 16 rotates the large gear wheel 22, which in turn rotates the shaft 21. This shaft rotates the crank disk 23, which causes the piston 67 (see Fig. 4), to be reciprocated, for pumping the gasoline or the like from the tank 73, through pipe 42 into the dispensing tank 41. This pumping action is continued until just the correct amount of the gasoline or the like has been pumped into the dispensing tank 41, when the float-ball 53 will be sufficiently elevated to move the rod 44 upwardly, whereby the free end of the dog or pawl is withdrawn from the opening or notch 36. When this takes place the spring

33 at once moves the rod or bolt 30, head 29, and arm 28 to the left into their normal position. The valve structure 59 is now opened and the bolt 25 returned to engagement with the gear wheel 22 to prevent rotation of the same. The gasoline or the like will now discharge through the pipe 57. The small gear wheel 16 engaging the large gear wheel 22, is now held against rotation.

10 When the crank or handle 10 is released, the gear wheel 16 being relatively stationary, as above stated, the spring 19 will turn the ratchet wheel 11 and associated elements counter-clock-wise so that the teeth 13 and 15 14 will be spaced for substantially a quarter of a revolution. When the level of the gasoline within the tank 73 drops below a certain point, the float 76 descends carrying with it the rod 77, which swings the lever 78. This movement of the lever 78 moves the link or rod 84 upwardly to swing the coin chute section 82 upwardly, whereby the coin is returned to the operator.

It is to be understood that the form of my 25 invention herewith shown and described, is to be taken as a preferred example of the same, and that certain changes in the shape, size and arrangement of parts may be resorted to without departing from the spirit of 30 the invention or the scope of the subjoined claims.

Having described my invention, I claim:—

1. A vending machine of the character described, comprising a dispensing receptacle, an outlet valve connected therewith, a pump to supply a liquid to the dispensing receptacle, driving mechanism for the pump, and common means to control the operation of the valve and driving mechanism.

40 2. In a vending machine of the character described, a dispensing receptacle, pumping mechanism to supply the liquid to be vended to the dispensing receptacle, means to operate the pumping mechanism, and automatic 45 float operated means mounted within the dispensing receptacle to be operated upon the supply of a predetermined amount of the liquid into the dispensing receptacle, for locking the pumping mechanism against 50 movement.

3. A vending machine of the character described, comprising a dispensing receptacle, an outlet valve connected therewith, a pump to supply a liquid to the dispensing 55 receptacle, driving mechanism for the pump, and means connected with the outlet valve to operate the same and adapted to engage the driving mechanism to lock it against movement.

60 4. In a vending machine of the character described, a dispensing receptacle, means for supplying a liquid to be vended to the dispensing receptacle, mechanism for operating the supply means, means including 65 a movable rod for controlling the movement

of the operating mechanism, a movable dog to hold the movable rod in a certain position when moved thereto, float means mounted within the dispensing receptacle and connected with the movable dog, and means to return the movable rod to its normal position upon being released.

5. In a vending machine of the character described, the combination with a dispensing receptacle, of pumping mechanism to supply the liquid to be vended to the dispensing receptacle, and float operated means mounted within the dispensing receptacle to automatically arrest the action of the pumping mechanism and discharge the liquid from the dispensing receptacle.

6. In a vending machine of the character described, a dispensing receptacle, a valve structure connected therewith for controlling the discharge of a liquid therefrom, means for supplying the liquid to the dispensing receptacle, and automatically operated means for simultaneously holding the liquid supply means against movement and opening the valve structure, whereby the liquid discharges from the dispensing receptacle.

7. A vending machine of the character described, comprising a dispensing receptacle, outlet means therefor, liquid inlet means for the receptacle, control means for approximately simultaneously rendering the outlet means inactive and the inlet means active, float operated means to hold the control means against movement in one direction when the inlet means is active and before a predetermined amount of the liquid has passed into the dispensing receptacle, and automatic means to move the control means in one direction when released by the float operated means.

8. A vending machine of the character described, comprising a dispensing receptacle, outlet means therefor, inlet means therefor, control means for closing the outlet means during the action of the inlet means whereby liquid is supplied to the dispensing receptacle and temporarily retained therein, and float operated means adapted to lock the control means against movement in one direction when the inlet means is active and before a predetermined amount of liquid has been supplied to the dispensing receptacle.

9. A vending machine of the character described, comprising a dispensing receptacle, an outlet valve therefor, pumping means to supply a liquid to the dispensing receptacle, driving means for the pumping means embodying a rotatable element, a reciprocating member having connection with the outlet valve and provided with means to engage the rotatable element, a spring to move the reciprocating member in one direction, a latch to temporarily hold the recipro-

120
125
130

catory member when it is moved to a position in opposition to the spring, and float controlled means to move the latch.

10. A vending machine of the character described, comprising a dispensing receptacle, an outlet valve therefor, pumping means to supply a liquid to the dispensing receptacle, driving mechanism for the pumping means, embodying a gear, a movable member provided with a holding element to engage with the teeth of the gear, and means connecting the movable member with the outlet valve.

11. A vending machine of the character described, comprising a dispensing receptacle, an outlet valve therefor, means for supplying a liquid to the dispensing receptacle embodying a movable element, a movable member having a portion thereof adapted to be brought into engagement with the movable element to hold the same against movement at the proper time, and connecting means between the movable member and the valve.

12. A vending machine of the character described, comprising a dispensing receptacle, an outlet valve therefor, supply means for the receptacle, means cooperating with the outlet valve and supply means to normally retain the valve open and the supply

means inactive and adapted upon movement in one direction to close the valve and render the supply means active, means to move the second named means in one direction, automatic means to move the second named means in an opposite direction, and float controlled means to hold the second named means temporarily in one position.

13. A vending machine of the character described, comprising a dispensing receptacle, a supply conduit leading into the same, a pump connected with the supply conduit, a manually operated crank shaft connected with the pump, a rotatable locking member mounted upon the crank shaft, a reciprocating member provided with a dog to engage the rotatable locking member, means to move the reciprocating member in one direction so that the dog will release the rotatable locking member, a latch to temporarily hold the reciprocating member in such position and float operated means to move the latch.

In testimony whereof I affix my signature in presence of two witnesses.
